INVENTOR.
John A. Johnson
BY John E. Stoyke
ATTORNEY

Patented Jan. 3, 1928.

UNITED STATES PATENT OFFICE.

JOHN A. JOHNSON, OF MINNEAPOLIS, MINNESOTA.

MAIL BOX.

Application filed September 13, 1924. Serial No. 737,452.

This invention relates to mail boxes and particularly to such boxes having a mail receiving slot provided with a closure and means for locking said closure.

As is well known, post office regulations now require that groups of mail boxes, such as those placed in apartment houses, be provided with locked closures for the mail receiving slots. Under these regulations the mail carrier or postman is provided with a key by which he may simultaneously, open all of the boxes of a group, thus obviating the necessity for opening individual boxes for the delivery of mail. However, as far as applicant is aware, all of such group locking devices heretofore provided require expensively constructed boxes and the time and work attendant upon operating the same is excessive.

It is my object to provide novel and efficient means for simultaneously locking and unlocking the mail boxes of a group.

A further object is to minimize the cost of such boxes and at the same time to simplify the work of delivering mail thereto by providing group closing and locking mechanism of unusually simple and easily operable construction.

In the accompanying drawings I have illustrated the best form of my device at present known to me. Referring to the drawings, Figure 1 is a front elevation of a group of mail boxes having my improved closing and locking mechanism applied thereto; Fig. 2 is a section taken on the line 2—2 of Fig. 1; Fig. 3 is a section taken on the line 3—3 of Fig. 1 and Fig. 4 is a fragmentary, vertical section through an alternate form of box.

In the drawings I have illustrated my invention applied to a group of eight built-in mail boxes 5 suitable for use in apartment houses, the boxes being arranged in an upper and a lower row. Each box is provided with a mail receiving slot 6 and a door 7 for the withdrawal of mail by the several occupants of the apartments. The front wall 8 of each box is formed with a forwardly projecting portion 9, across the top of which the slot 6 extends. A closure 10 for each of the slots 6 is formed integral with a pivoted portion 11 of the back wall of the box. To pivotally support the part 11, flanges 12 are formed on the lateral edges thereof and are perforated to receive a horizontal rod

13. This rod is secured at its ends in vertical partitions 14 at the lateral sides of the box. A flange 15 on the forward end of the closure 10 facilitates the insertion of mail in the slot 6. By reason of its forwardly leaning position, the part 11 under gravity normally maintains the closure 10 in closed position.

My improved locking mechanism consists of a horizontal rod 16 extending through the tops of the boxes in each row, locking fingers 17 fast on said rods, and a master lock 18 connected as hereinafter described to the rods 16 whereby the fingers 17 may be actuated to either free or prevent movement of the closure 10. As clearly shown in Fig. 2, the lock 18 is disposed with its bolt 19 movable downward and adapted to engage a horizontal portion 20 of a vertically slidable rod 21. This rod 21 is normally supported and maintained in engagement with the bolt 19, by a coiled compression spring 22. At its lower end the spring 22 engages an angle clip 23 mounted on the inner surface of a front casing 24, and the clip 23 and similar clips 25 on the wall 24 constitute guides for vertical movement of the rod 21. Fast on each of the rods 16 and extending into suitable apertures in the vertical rod 21 is a pair of cranks 26 adapted to turn the rod 16 when the rod 21 is moved vertically. The position of the fingers 17 on the rod 16 is such that when the locking bolt 19 is extended downward, the free or forward ends of said fingers are in proximity to the back of the part 11, where they prevent opening of the door 10. A pair of the fingers 17 are placed on the rod 16 opposite each of the doors 10. If desired, the fingers 17 may be made short enough to permit sufficient opening of the closure 10 for the insertion of thin objects, such as special delivery letters.

To minimize the force required to operate the lock 18, I prefer to place the spring 22 under just sufficient compression to support the rod 21; and the fingers 17 and cranks 26 are provided with suitable counterweights 27. To insure proper operation of the rod 21, even if the spring 22 should fail to lift said rod, I provide a pin 28, which is fixed in the rod 21 and projects through a vertical slot 29 in the wall 24. This pin 28 may be manipulated when the bolt 19 is retracted to free the fingers 17 from the closures 10, and may also be used to oppose the action

of said spring and thus relieve pressure on the bolt when it is desired to extend the same.

In the alternate form of my device shown in Figure 4, I have illustrated a mail receiving slot 30 of common type which is provided with an inwardly swinging closure 31. The mechanism for operating the rod 16 is identical in this alternate form with that described above, and the fingers 32 are merely arranged to be directed at the back of the closure 31 when in locked position. To unlock the closure 31, the fingers 32 are merely tilted out of the path of said closure.

As will now be readily understood, the lock 18 may be operated by a key to withdraw the bolt 19. Upon the withdrawal of the bolt, the rod 21 is raised by the spring 22 to tilt the fingers 17 to their dotted line position shown in Figure 3, thus simultaneously freeing all of the closures 10. The closures 10 may now be opened as indicated in dotted lines in Fig. 3 for the insertion of mail. After the mail has been distributed to the several boxes, the slots 6 are closed by the closures 10 and may be simultaneously locked by manipulating the lock 18 to extend the bolt 19. This, as will be readily understood, moves the finger 17 into the path of the closures, as shown in full lines in Fig. 3.

Obviously, an indefinite number of the boxes 5 may be placed in a single group and all of the boxes may be made accessible for the delivery of mail by manipulating a single lock. The cost of the locking mechanism for a large group is only slightly greater than that for a smaller group.

Having described my invention what I claim as new and desire to protect by Letters Patent is:

1. The combination with a group of mail boxes each having a mail receiving slot and a normally closed door for said slot arranged to be opened inward to permit insertion of the mail, of a series of fingers tilttable into and out of the path of said doors and arranged when in said path to prevent opening the doors, a rod operatively connected to said fingers for simultaneously moving the same into and out of the path of said doors, and a master lock arranged to actuate said

rod and adapted to be manipulated to simultaneously secure said fingers in the path of said doors.

2. The combination with a group of mail boxes disposed in horizontal rows and each having a mail receiving slot and an inwardly movable closure for said slot, of a lock rod for each row, a series of locking elements movable by said rods into and out of the path of said closures and arranged when in said path to prevent opening the closures, a substantially vertical rod adapted to simultaneously actuate said lock rods, and a master lock arranged to operate said vertical rod and adapted to be manipulated to simultaneously secure said locking elements in the path of said closures.

3. The combination with a group of mail boxes, disposed in a horizontal row and each having a mail receiving slot and an inwardly movable closure for said slot, of a rod extending through the several boxes adjacent to said closures, fingers rigidly mounted on said rod and movable thereby into and out of the path of the several closures, a master lock, and linkage between said lock and rod whereby said fingers may be simultaneously moved into and out of the path of said closures by the manipulation of said lock.

4. The combination with a group of mail boxes disposed in a plurality of horizontal rows, each having a mail receiving slot, a closure for each of said slots pivoted within the mail box and arranged to be opened inwardly, a projection on each closure extending out through said slot and constituting a handle for opening the closure, a horizontal rod extending through the several boxes of each row adjacent to said closure, said rod being revoluble about its longitudinal axis, locking fingers fixed on said rod and arranged to be moved thereby into and out of the path of the several closures, whereby said closures may be held in closed position, a master lock and a substantially vertical rod slidable longitudinally and connected to the several horizontal rods, said vertical rod being operable by said lock.

In testimony whereof, I have hereunto signed my name to this specification.

JOHN A. JOHNSON.
